The ornamental design for a storage rack for compact discs and video cassettes, as shown and described.

DESCRIPTION

FIG. 1 is a front elevation view of a storage rack for compact discs and video cassettes illustrating my new design;

FIG. 2 is a right side view thereof, the left view being identical in appearance;

FIG. 3 is a rear elevation view thereof;

FIG. 4 is a top plan view thereof; and,

FIG. 5 is a bottom plan view thereof.

FIG. 1.

FIG. 2.

FIG. 3.

FIG. 4.

FIG. 5.
